Primary Examiner — Jack Reickel*Assistant Examiner* — Keith J Wilson(74) *Attorney, Agent, or Firm* — Nirav D. Parikh; Edgar A. Zarins(57) **CLAIM**

The ornamental design for a shower system, as shown and described.

DESCRIPTION

FIG. 1 is a perspective view of a shower system showing my new design;

FIG. 2 is a left side view thereof;

FIG. 3 is a front elevational view thereof;

FIG. 4 is a top plan view thereof;

FIG. 5 is a bottom view thereof;

FIG. 6 is a right side view thereof; and,

FIG. 7 is a rear view thereof.

The broken lines represent portions of a shower system and form no part of the claimed design.

1 Claim, 6 Drawing Sheets(56)
